UNITED STATES PATENT OFFICE.

WILLIAM HERBERT GATES, OF NEW HAVEN, CONNECTICUT.

COLLAPSIBLE TAP.

Application filed March 21, 1922. Serial No. 545,403.

To all whom it may concern:

Be it known that I, WILLIAM H. GATES, citizen of the United States, residing at New Haven, in the county of New Haven 5 and State of Connecticut, have invented certain new and useful Improvements in Collapsible Taps; and I do hereby declare the following to be a full, clear, and exact description of the invention, such as will 10 enable others skilled in the art to which it appertains to make and use the same.

My invention relates to taps of the collapsible type, and is an improvement on my former Patents No. 1,209,139, of 1916, and 15 No. 1,358,075, of 1920. In said former patents, the threading dies or chasers were provided with cam grooves registering with cam studs for controlling the radial movement of the chasers. While this arrangement 20 was found suitable for small taps, it did not provide the necessary strength and stability required for large taps. In the present invention, the chasers are actuated and controlled by carriers having preferably the same radial movement as the chasers. It further consists in properly supporting the chasers during the threading 25 operation.

Referring to the accompanying drawings, 30 wherein the same figures of reference indicate like parts throughout the several views;

Figure 1 represents the assembled tap showing the chasers thrown out in operative position;

Figure 2 is a front elevation of Figure 1;

Figure 3 is a similar view with the front plate and chasers removed;

Figure 4 is a detail inside view of the 40 sliding shell carrying the cam studs and trip lever, also cross sectional view of the support for the chasers and its actuating bolt;

Figure 5 is a detail front elevation of 45 the tap body;

Figure 6 is a side elevation of the tap body with the sliding shell, chasers and chaser carriers removed, cross sectional view of die support actuating bolt, and springs 50 adapted to be located between the head of the die body and sliding shell;

Figure 7 is a sectional view of the die body and sliding shell on line 7—7 of Figure 2, showing the chasers and their carriers expanded, and the die support in its

advanced position to support the outer ends of the chasers;

Figure 8 is a detail view of the chasers and their carriers collapsed, also broken view of the retreated chaser support; 60

Figure 9 is a detail end elevation of two of the chaser carriers, and cross sectional view of the internal chaser support;

Figure 10 is a detail broken elevation of the tap body and locking bolt, and 65

Figure 11 is a detail side elevation of one of the chaser carriers.

The body of the tap comprises the end 1 having the radial slots 2 for the radially operating chasers 3, and 4 is an enlarged 70 part or head having the radial slots 5 opening into the radial slots 2 for the radially operating chaser carriers 6. The shank 7 of the tap body is adapted to enter a rotatable tool holding turret head or like support, not shown. 75

The shell 8 is slidably mounted on the shank 7 and the head 4 of the tap body, and is provided with the openings 9, Figure 4, for the reception of the ends of the 80 cam studs 10 having the cam projections 11. These studs are secured to the shell by the pins 12, Figure 7. The head 4 of the tap body, Figure 5, is provided with the openings 13 in alignment with the cam studs 10 and through which openings the studs have 85 a free longitudinal movement.

The chaser carriers 6 are mounted, as before mentioned, in the radial slots 5 of the tap head 4, Figures 3 and 7, and each are 90 provided with the cam grooves 14, Figure 11, for the reception of the cam projections 11 of the studs 10. The plate 15 for retaining the carriers in place is secured, Figures 1 and 2, to the head 4 by the screws 16. 95

The radially operating chasers 3 are each provided with the projections 18 adapted to register, Figures 7 and 8, with the recesses 19 formed in the carriers 6, so that both chasers and carriers will move in unison 100 through their respective slots. The inner face of the shoulders 20 of the chasers rest against the outer surface of the plate 15 to support and insure the dies moving parallel with the carriers 6. The plate 21, Figure 1, 105 is secured to the die end 1 of the tap body by screws 22, and the chasers will have a free radial movement between the plates 15 and 21.

The springs 23 have one end located in 110

the openings 24, Figure 4, of the sliding shell, and the openings 25, Figure 6, of the head 4.

26, Figure 10, is a locking bolt mounted in 5 the opening 27 of the head 4, and the opening 28 of the sliding shell 8, Figure 4. This bolt has the notch 29 adapted to interlock with the trip lever 30, Figure 4, by means of the spring 31. This trip lever is located 10 in the recess 32, see also Figure 1, and is journaled on the screw 33 projecting through the flange 34. The locking bolt 26 is adjusted to bring its notch 29 in proper 15 relation with the trip lever 30, by means of the screw 35, Figure 10.

The interior support for the outer end of the expanded chasers comprise the shank 36 having a longitudinal movement in the bore 37 of the shank 7 of the tap body, Figure 7, 20 and is secured to the sliding shell 8, Figure 4, by the bolts 38. The outer end of said chaser support has the taper head 39 adapted to engage with the taper faces 40 of the chasers when said chasers are expanded or 25 forced outward into threaded position, and thus provide a firm support therefor. The intermediate fluted portion 41 of the chaser support provides the necessary room, Figure 9, for the inward travel of the chaser carriers 6 when the chasers are collapsed or 30 withdrawn. 42 is an elongated opening through the shank 7, Figure 6, to afford the necessary movement of the bolt 38 in connection with the reciprocal travel of the 35 sliding shell 8.

In operating the tap, the sliding shell 8 is interlocked with the tap head 4 either manually or by bringing the shell forcibly against a stationary support, such, for instance, as the support 43, Figure 7, which support may be connected with the machine operating the tap. Interlocking the shell will have compressed the springs 23 and advanced the cam studs 10 to force out the

carriers and the chasers, and at the same 45 time, advance the chaser support into engagement with the chasers as shown in Figure 7. When the tap has traveled its predetermined distance and completed its work, the trip lever 30 will contact with another 50 stationary support, not shown, and release the sliding shell 8 which will be forced back by the stored up tension in the springs 23. This retreat of the shell will cause the 55 chasers and their carriers to collapse as shown in Figure 8, and permit the tap to be withdrawn from the recently threaded work. The externally located means for locking and unlocking the sliding shell are 60 well known and commonly employed in connection with die heads and collapsible taps.

The principal feature of the present invention resides in controlling the movement of the chasers through the medium of carriers operating in unison therewith, and while I show the carriers actuated by cam studs carried by a sliding shell, I hold myself at liberty to employ any well known 65 mechanical means for actuating said carriers.

Having thus described my invention what I claim is:—

A collapsible tap comprising a body having radial slots, chasers operatively mounted therein, an enlarged portion or head having radial slots opening into the chaser slots, chaser carriers mounted in the radial slots of the head, said carriers having cam grooves, said chasers and carriers operatively connected together, an operating member, cam studs carried thereby having cam projections registering with the cam grooves of the carriers, a locking bolt and trip lever, and a centrally located chaser support carried by said operating member. 75 80 85

In testimony whereof I affix my signature.

WILLIAM HERBERT GATES.
